Patented Aug. 20, 1918.

5 Inventor
Leopold Powell
By his Attorney
Charles H. Wilson.

UNITED STATES PATENT OFFICE.

LEOPOLD POWELL, OF NEW YORK, N. Y.

CIGAR-BOX.

1,276,409.

Specification of Letters Patent. Patented Aug. 20, 1918.

Application filed May 26, 1916. Serial No. 99,985.

To all whom it may concern:

Be it known that I, LEOPOLD POWELL, residing at New York, in the county of New York and State of New York, have invented 5 certain new and useful Improvements in Cigar-Boxes, of which the following is a specification.

This invention relates to a cigar box, and the object thereof is to provide a box which 10 will comprise means for maintaining the cigars, or the like, therein in a suitably moistened condition.

A more detailed object is to provide a moisture carrying element and to provide 15 means associated therewith for conserving the moisture therein.

A further object is to provide means whereby the moisture carrying element may be inserted and removed without disturbing 20 the cigars within the box.

A further object is to make the moisture carrying element in such form that it may be employed for an additional purpose, for 25 instance an advertising purpose, when desired.

Other objects and aims of the invention, more or less specific than those referred to above, will be in part obvious and in part 30 pointed out in the course of the following description of the elements, combinations, arrangements of parts and applications of principles, constituting the invention; and the scope of protection contemplated will be 35 indicated in the appended claims.

In the accompanying drawings which are to be taken as a part of this specification, and in which I have shown a merely preferred form of embodiment of the invention:

Figure 1 is a perspective view of a box 40 constructed in accordance with the provisions of this invention.

Fig. 2 is a transverse sectional view taken upon the plane of line II—II of Fig. 1.

Fig. 3 is a similar sectional view taken 45 upon the plane of line III—III of Fig. 1, and

Fig. 4 is a perspective view of the moisture carrying element removed.

Referring to the drawings for a detailed 50 description of the structure which is illustrated therein, the reference character L indicates the front wall of the box. This is provided with an opening 1 therethrough, through which the moisture carrying element G is adapted to be slid.

When the moisture carrying element G is in position within the box, it rests flat against the upper surface of the bottom wall H of the box.

A false bottom member 2 is provided within the box directly above the moisture carrying element, said false bottom being spaced from the bottom H to provide a compartment into and out of which the moisture carrying element may be slid through the opening 1.

The false bottom may be made of any suitable material, but is preferably made up of wood, the same as the remainder of the box. Its upper surface, however, is coated with some waterproof material, as 3, which will present a relatively cool surface to the atmosphere at all times.

Preferably a sheet of oiled silk is employed for this purpose, the same being stuck directly to the surface of the wood.

A plurality of openings 4 are provided through the false bottom but not through the coating. The moisture from the moisture element G will maintain the coating covering the openings in an especially cooled condition.

The moisture element G may be made up of any material, but this also preferably comprises a sheet of wood having a sheet of absorbent material, as blotting paper 5, stuck to its upper surface.

A handle member 6 is provided whereby the moisture element may be readily withdrawn at any time.

The coating carried by the false bottom 2 constitutes the same as an efficient barrier to moisture tending to rise upwardly from the moisture element at all points even where the openings 4 occur. These openings may be proportioned and disposed in such manner as to provide just sufficient cool surface for accomplishing the purpose intended. The false bottom thus will constitute means for conserving the moisture within the moisture carrying element.

In practice the coating 3 upon the false bottom will be affected more or less by the presence of moisture directly beneath it and will be maintained cool. This cool surface will tend to condense moisture from the surrounding atmosphere. The portions of the coating covering the openings will be especially effective as a condensing medium. The false bottom 2 thus becomes a moisture gathering element and it is maintained cool

by the moisture carrying element, so that it will better perform its function. The condensed moisture will materially aid in maintaining the contents of the box in a suitable condition.

Wherever desired the moisture carrying element G may be made use of as an advertising medium. For this purpose any suitable printed matter, or the like, may be im-
10 pressed upon one or both sides. The handle member 6 may be utilized as a supporting element, as shown in Fig. 4 of the drawings.

Having thus described my invention what I claim as new and desire to secure by Letters Patent is:

1. In a cigar box, a bottom wall in said box adapted to permit the passage of moisture therethrough, a moisture gathering element comprising a coating of waterproof material upon the upper face of said bottom wall, and a moisture carrying element arranged beneath said bottom wall in close juxtaposition thereto to maintain said bottom wall and coating cool.
2. In a cigar box, a bottom wall in said box adapted to permit the passage of mois-

ture therethrough, a moisture gathering element comprising a coating of oiled silk upon the upper face of said bottom wall, and a moisture carrying element arranged beneath said bottom wall in close juxtaposition thereto to maintain said bottom wall and coating cool.

3. A cigar box having a false bottom therein, a moisture carrying element disposed within said box beneath said false bottom, the false bottom having an opening therethrough, and a moisture proof coating upon the top of said false bottom.

4. A cigar box comprising a cigar compartment and a moisture compartment, and a water proof partition disposed between said compartments and providing a moisture gathering element to supply moisture to the cigar compartment.

In testimony whereof I affix my signature in the presence of two witnesses.

LEOPOLD POWELL.

Witnesses:

MARY KLEIN,
DAVID EPSTEIN.
